Attorney, Agent, or Firm—Richard B. O'Planick*[57] **CLAIM**

The ornamental design for a domed lid for trash container, as shown and described.

DESCRIPTION

FIG. 1 is a top left front perspective view of a domed lid for trash container showing my new design;

FIG. 2 is a top plan view thereof;

FIG. 3 is a bottom plan view thereof;

FIG. 4 is a front elevational view thereof;

FIG. 5 is a side elevational view thereof; the rear elevation and opposite side views being mirror images;

FIG. 6 is a top, left and front perspective view of a second embodiment of the domed lid for trash container;

FIG. 7 is a top plan view of FIG. 6;

FIG. 8 is a bottom plan view of FIG. 6;

FIG. 9 is a front elevational view of 6; and,

FIG. 10 is a side elevational view of FIG. 6, the rear elevation and opposite side view being mirror images that shown.
